UNITED STATES PATENT OFFICE.

LUIGI EMANUELI, OF MILAN, ITALY, ASSIGNOR TO SOCIETA ITALIANA PIRELLI, OF MILAN, ITALY, A CORPORATION OF ITALY.

MACHINE FOR TAPING JOINTS OF ELECTRIC CABLES.

Application filed November 19, 1926, Serial No. 149,446, and in Italy August 10, 1926.

Cables designed to be located underground, either in conduits or buried in the earth to carry electricity, are of necessity made in lengths or sections which after being laid in place have to be united one to the other to form a continuous conductor. In the simplest form such cables for high tension purposes comprise a conductor either stranded or solid, a covering of insulation therefor such as impregnated paper tape, and a lead sheath. In joining the ends of two adjacent sections the lead sheath is cut back for a certain distance and the insulation, commonly referred to as factory insulation, is also cut away, usually on a taper, to expose the ends of the conductors. The ends of the conductors are then united by a sleeve which is soldered to both, after which tape is applied to the desired thickness and the whole enclosed by a casing which is soldered to the lead sheath. The space between the tapered joint and the metal casing is then filled with an insulating compound.

The joints are the most delicate parts of a cable and therefore must be very carefully and accurately made. The tape used in making the joint must be uniformly and tightly wound on the connector and over the cut-away factory insulation which latter usually is tapered from about the full diameter at the outer ends of the joint to the connector. In handling the tape care must be exercised by the joiner to have clean hands so as to avoid leaving any traces of moisture or acidity on the tape as it is well known that both of these noticeably reduce the breakdown voltage of the joint. As a general thing, this taping of the joint has been done by hand which consumes a great deal of time. An attempt has been made to tape these joints with a machine but such machine is relatively slow in operation because it applies only a single tape at a time, and necessitates considerable handling of the tape by the joiner.

It is not uncommon in high tension cables to have the taped portion of the joint 36 inches long with a maximum diameter at the center of 6 inches. Such a joint may require as much as 4500 feet of one inch paper tape involving about 6000 turns to complete it, from which will readily be appreciated the large amount of work involved and the high cost thereof.

My invention has for its object the pro-

vision of a joint-taping machine of improved construction which will rapidly and accurately apply tape to a conductor joint, and in the use of which the opportunity for the hands of the joiner to come into contact with the surfaces of the tape is reduced to a minimum.

For a consideration of what I believe to be novel and my invention, attention is directed to the accompanying description and the claims appended thereto.

In the accompanying drawing which is illustrative of my invention, Fig. 1 is a diagrammatic view of the machine showing a plurality of tapes being simultaneously wound on a conductor joint; Fig. 2 is an end view of the same; Fig. 3 is a similar view showing how the friction on the tape can be increased; Fig. 4 is a view of the template employed to give the proper outline to the joint and which also serves as a tape-cutting means; Fig. 5 is a plan view of the machine without the rolls of tape; Fig. 6 is an end view of said machine and Figs. 7 and 8 illustrate forms of joints adapted to be taped by my improved machine.

In Figs. 1, 7 and 8, 10 and 11 indicate sections of a conductor which are to be united and insulated. 12 indicates a connector for uniting the conductor ends and through which current flows. The factory wound or applied insulation 13 may be cut away on a curve as indicated at 14 or it may be cut away on a long taper as indicated at 15 in Fig. 8. Around the connector and covering the adjacent ends of the factory insulation is wound insulation which advantageously but not necessarily may be a roll of impregnated paper sheeting 16, said paper being wider at the inner end and gradually decreasing in width to the outer end. The paper is first loosely wrapped around the connector and then tightened by winding from the outer turn. The spaces between the edges of the roll and the factory insulation are then filled with treated tape 17 which may be wound by hand or by a small machine, as desired. The object is to make the parts thus far assembled as nearly as possible into a true cylinder and prevent voids.

Referring now to the taping machine, a carrier is provided which comprises a pair of end heads 18 and 19 which are connected by axially-extending rods or tubes 20 and

- which maintain them in spaced relation. As shown both rods and tubes are employed, the rods uniting the heads and the tubes acting as spacers. The heads are mounted to turn freely on bearings 21 which are made in halves and clamped by bolts on the lead covered ends of the cable. The bearings have flanges 21^a to prevent relative endwise movement of the machine and conductor. 5 Each head is made in two parts which are united by a hinge 22, Fig. 6, on one side of the axis of the cable, and by a removable pin 23 on the other. Splitting the heads in this manner facilitates mounting the machine in place on the cable. Since this is customarily done in a manhole where space is at a premium the advantage of the construction will be apparent. One or both of the heads are provided with handles 24 for 10 turning the carrier to apply the tapes to the joint.

Instead of applying only a single tape at a time which is a slow process whether done by hand or otherwise, I simultaneously apply 15 a large number of impregnated tapes and so arrange them that the tape from one roll partly overlaps the tapes from two other rolls. This is accomplished by a very simple but effective arrangement. Two sets of 20 rolls 25 and 26 are provided, one set being mounted on one side of the joint and the other set on the other side. By preference the axes of the two sets of rolls are in the same diametrical plane but this exact arrangement is not essential. The real point 25 involved is that the tape from one roll is laid on first and this is followed by the tape from another roll and in such manner that one overlaps the other. In other words, the 30 axis of one set of rolls is angularly displaced with respect to the axis of another set of rolls, and the rolls of one set are axially displaced or staggered with respect to those of the second set in an axial plane whereby the 35 tapes are caused to overlap. As an illustration but not as a limitation of my invention, I have constructed a machine utilizing 36 rolls of one inch tape in each set so that a total of 72 rolls of tape are simultaneously 40 applied to the joint.

The rolls may be mounted about the rods or tubes which connect the end heads as shown in Fig. 1 but a better way is to mount them on separate supports such as thin-walled tubes 27 shown in Fig. 5. The rolls of each set are in frictional contact with each other at the sides so as to put tension on each tape 28. At the end of each set is an adjustable means to increase the friction. 45 The rolls may turn in the same direction but a better way is to have alternate rolls in each set turn in opposite directions since the friction effect is then distributed uniformly over the entire assemblage rather than being limited to end friction only. This reversal of

motion is indicated in Fig. 2 where the small full line arrows indicate the direction of rotation of one-half of the rolls in one set and the dotted line arrows that of the other half of the set. The large arrow indicates 50 the direction of rotation of the frame with respect to the axis of the conductor. Instead of passing the tapes directly to the joint from the rolls they may be first passed over two of the head connecting rods 20 as 55 shown in Fig. 3. This further increases the tension on the tapes.

In order that the jointer may determine the correct amount of tape to be wound on the joint and obtain the correct shape to 60 properly insulate the joint to distribute the electrical stresses, a template 29 is provided which is removably attached to the end heads. The template is also used as a cutting edge by means of which the jointer can 65 tear off the unused portion of each roll when the desired amount of tape from each roll has been wound on the joint.

Referring more specifically to Figs. 5 and 6, 18 and 19 indicate the divided or hinged 70 end heads and 21 the supporting bearings therefor. The heads are slotted at 30 to permit of the rolls and their supports being mounted in place by an inward movement of the supports toward the conductor. Each 75 support comprises a tube 27 into the ends of which extend hollow members 31. Each member has a screw stud 32 with square base, on the threaded end of which is seated a nut 33 that is moved by the small hand-wheel 34. The member 31 has a shoulder which engages the head and forms a seat. 34 at the 80 right hand end indicates an adjusting nut and 35 a lock nut. Between the nut 35 and the last roll of the set are two washers 100 splined on the member 31 and between which are spring fingers 36, the purpose of which is to equalize the pressure over the side of the roll instead of localizing it at one point 105 as might otherwise be the case. By changing the position of the nuts the rolls can be adjusted endwise to obtain the proper overlap of the sets of rolls on both sides of the 110 carrier.

Referring to the left hand end, 37 indicates a collar which is splined on the member 31, said collar exerting endwise pressure on the series or set of rolls. Outside of it is a coiled compression spring 38 which exerts pressure on the collar at all times. The member 31 is held in the left hand head in the same manner as the one at the opposite 120 end.

The template 29 comprises a rather thin piece of sheet metal the inner edge of which defines the finished shape of the joint. It is shown diagrammatically in Fig. 4 and as constructed in Fig. 5. The corners of the said inner edge serve as cutting edges on which the tapes can be torn. These tapes

are usually made of tough paper impregnated with a suitable insulating compound although tapes of other material may be used. The template is held at its ends by 5 slotted clamps 39 which engage the heads, screw studs and wing nuts 40.

The joints having been prepared as indicated in Figs. 7 or 8, the machine is mounted in place on the conductor with a full set of 10 rolls on each support 27. The joint may be given a partial or complete coat of sticky compound and the ends of all the tapes are pressed thereon, or the tapes themselves may be sufficiently sticky to adhere to the 15 joint. The machine is then turned by hand thus winding on the joint layers of tape, a part from one set of rolls and the balance from the other, the tape on one set overlapping that from the other as clearly shown in 20 Fig. 1. This offsetting of one set of rolls with respect to the other is attained by positioning the spring pressed washers 36 on one support 27 a little in advance of those on the other support. As the work proceeds 25 and the end layers or turns of tape reach the template the jointer tears the tape at these points. The successive tapes are torn in the same manner, one after the other, until the whole joint assumes the shape shown 30 in the lower half of Fig. 4. The last tape is stuck down either by reason of its impregnating compound or by other adhesive. The fact that the tape from each roll except the last is overlapped by another tape results 35 in binding them all firmly in place. The fact that the machine winds many tapes and over the full length of the joint at the start gradually decreasing in number as the final contour is approached, results in a very 40 great saving of time over winding a single tape back and forth. It saves much handling of tape, thereby avoiding the danger of moisture and acidity due to contact of the jointer's hands therewith.

45 It is to be noted that with this machine the tape from each roll is built up layer by layer, in a direction perpendicular to the axis of the conductor instead of progressing from one end of the joint to the other as is 50 the case where a single tape is applied either by hand or machine, and that the tape in each turn or layer from one side is overlapped by parts of two other tapes from the other side. This results in an interlocking 55 of the tapes which makes a good electrical and mechanical insulating covering for the joint. Since the rolls of each set are in side- 60 wise contact it follows that the tapes from any one set when wound on the joint are in edgewise contact which prevents the formation of voids which are highly injurious in joints of this character. Moreover, the tapes are uniformly tensioned which is conducive to good results. This is chiefly due to the 65 fact that the rolls are in frictional contact

on each side so that one roll acts as a brake or friction device for the others.

After the joint is properly taped as described it is encased as usual in a closed metallic covering the ends of which are soldered to the lead sheath. These coverings have one or more normally closed openings 70 through which insulating compound may be forced to fill all spaces between the taping and the walls of the covering. 75

Another and important feature of the invention resides in the fact that all of the tape for a given joint is mounted in the machine before the taping operation is started, and where the total amount of tape used is 80 of the order of 4500 feet this saves a great deal of time. Furthermore, each tape is complete in itself, and hence it is unnecessary to make joints at intermediate points therein as is the case where a single tape is 85 used. Where a single tape is used according to previous practice, it follows that each roll must of necessity be of relatively small diameter, and as soon as it is exhausted a 90 succession of other rolls have to be used, joining one to the other. This requires of course additional handling of the tape by the jointer which is objectionable for the reasons previously stated and also because it consumes a considerable amount of time. 95

What I claim as new and desire to secure by Letters Patent of the United States, is:—

1. In a taping machine, the combination of a carrier adapted to be rotated about a stationary body which is to be taped, means for preventing relative axial movements of the carrier and work, and rolls of tape mounted on the carrier and arranged in different distinct sets, the axes of which extend parallel to the axis of the body, said 100 sets of rolls being angularly and axially displaced one set with respect to the other so that as the tapes are wound on the body the turns from each roll of either set partially overlap those of two rolls of the other set. 110

2. In a taping machine, the combination of a carrier adapted for relative rotation with respect to the work, means for holding the carrier and work against relative axial movement, and a plurality of distinct sets of rolls of tape pivotally mounted on the carrier and which are angularly and axially displaced one set with respect to the other on the carrier so that as the tapes are wound on the work by rotating the carrier the successive 105 turns partially overlap, and tension-creating means for each of said tapes. 115

3. In a taping machine, the combination of a carrier mounted to rotate about the work, an axially-extending supporting member carried thereby, a row of contacting rolls of tape mounted to turn on the member, some in one direction and the remainder in the opposite direction as the carrier is rotated about the work, and friction-creating means 120 125 130

- which exert endwise pressure on the rolls to maintain them in contact and thereby impart tension to the tapes.
4. In a taping machine, the combination of a rotatable carrier which surrounds the work, an axially-extending supporting member mounted thereon, a set of rolls of relatively narrow tape arranged side by side in frictional engagement and mounted to turn on the member, alternate rolls turning in one direction and the remainder in the opposite direction during the winding operation, and means for exerting endwise friction on the rolls to impart tension to the tapes.
5. In a machine for taping electric conductor joints, the combination of bearing members adapted to be supported by the conductor on opposite ends of the joint, a carrier mounted to turn on the bearing members, and sets of rolls of tape pivotally mounted on the carrier to turn independently thereof, said sets being angularly and axially displaced one with respect to the other so that as the carrier is rotated the tapes, as they are unwound from one set of rolls and wound on the conductor, will be partly overlapped by the tapes from another set.
6. In a machine for taping electric conductor joints, the combination of a carrier mounted to be revolved around the axis of the conductor, sets of pivotally-mounted rolls mounted on the carrier, the rolls of one set being axially-displaced with respect to those of the other set by an amount less than the width of the tape, and a template mounted on the carrier which determines the amount of tape that can be wound on the joint from any one of the rolls.
7. In a machine for taping electric conductor joints, the combination of a carrier which bridges the joint and is supported at its ends so as to be rotatable about the axis of the joint, sets of rolls of tape pivotally mounted on the carrier so as to wind tape on the conductor as the carrier is rotated, the tapes from one set of rolls overlapping those from another set, and an axially-extending template mounted on the carrier heads which determines the amount of tape that can be wound on the joint from said sets of rolls.
8. In a machine for taping electric conductor joints, the combination of a carrier which bridges the joint and is supported at its ends so as to be rotatable about the axis of the joint, a set of contacting rolls of tape pivotally mounted on the carrier so as to wind tape on the conductor as the carrier is rotated, the tape being fed from one side of a part of the rolls and from the other side of the remainder so as to cause relative rotation of the rolls in opposite directions, means for exerting endwise pressure on the rolls so that the mutual friction thereby induced between them produces tension on the tapes, and a means which determines the amount of tape that can be wound on the joint from each of the successive rolls of tape.
9. In a machine for winding tape on intermediate portions of longitudinally extending objects, the combination of a pair of end heads each of which includes a pair of hinged elements to permit of its being mounted on and removed from the object, means which hold the heads in spaced relation, axially extending members which form angularly displaced supports, rolls of tape mounted in sets on the supports, said rolls being so positioned that the tape from one set when wound on the object will overlap the joints between turns of tape from the other set, and a template supported at its ends by the heads which determines the amount of tape that can be wound on the object from each of said rolls.
10. In a machine of the character described, the combination of a pair of end heads, each of which is made in two principal elements and united by a hinge so as to permit it to be closed and opened, members adapted to be clamped on the object to be taped and which form bearings for the heads, means which hold the heads in spaced relation and which also form tension means and guides for the tape as it is wound on the work, members which form pivotal supports, rolls of tape mounted on the supports, and additional means for imparting tension to the tape as it is being unwound from the rolls.
11. In a taping machine, the combination of a rotatable carrier which surrounds the work, sets of rolls of tape arranged to turn on parallel pivots on the carrier as the latter is rotated about the work, and means arranged to guide the tapes from the tops of alternate rolls and from the bottoms of the others, one set of rolls being displaced axially from the other set by an amount sufficient to cause one set of tapes to overlap the joints between adjacent turns of the other set of tapes when applied to the work.
12. In a taping machine, the combination of a carrier which surrounds the work, the two being relatively rotatable, sets of rolls of tape mounted on the carrier one set behind the other, the rolls of each set being in sidewise contact, and a pivot for each set of rolls which is mounted on the carrier, the rolls being positioned thereon in such manner that as the tapes from one set of rolls are wound on the work the tapes from a second set of rolls are wound on top of the first tapes, and in such manner that each second-named tape partially covers the two adjacent turns under it.
13. In a taping machine, the combination of a pair of end heads, means for supporting the heads in spaced relation, supports carried by the heads, rolls of tape mounted thereon in sidewise contact, a collar mounted

- at one end of each support to form a seat for the end roll, and a spring pressed collar located at the opposite end of each support to exert endwise pressure on the rolls.
- 5 14. In a taping machine, the combination of a pair of end heads, each of which has a slot, means for supporting the heads in spaced relation, supports having end portions which enter said slots, means for 10 clamping said portions in the head, rolls of tape mounted on said supports in sidewise contact, and means for exerting axial pressure on the rolls carried by the supports to maintain such contact.
- 15 15. In a taping machine, the combination of a pair of end heads adapted to be rotated about the work, means for supporting the heads in spaced relation and also carrying sets of rolls of tape, the latter being applied to the work as the heads and rolls are 20
- rotated, a template, the inner edge of which defines the contour of the structure built up on the work by unwinding of the tapes, and means for detachably securing the template on said rotatable structure. 25
16. In a taping machine, the combination of a rotatable structure, rolls of tape arranged in sets and mounted on the structure, the axes of the rolls extending parallel to the work, the rolls in one set being axially 30 displaced with respect to those of a second set so that as the tape is wound on the object the tape from one set of rolls overlaps the joints between adjacent tapes of a second set, and means for adjusting one set of rolls with respect to another set in an axial direction. 35

In witness whereof, I have hereunto set my hand this 16 day of November, 1926.

LUIGI EMANUELI.
